[57] CLAIM

The ornamental design for a covered food tray, as shown and described.

DESCRIPTION

FIG. 1 is a perspective view of a covered food tray in a partially opened configuration, showing my new design; FIG. 2 is a perspective view thereof in a closed configuration;

FIG. 3 is a front view thereof;

FIG. 4 is a rear view thereof;

FIG. 5 is a right side view, the left side being a mirror image thereof;

FIG. 6 is a top view thereof;

FIG. 7 is a bottom view thereof;

FIG. 8 is a perspective view of an alternate embodiment of FIG. 1; and,

FIG. 9 is a bottom plan view of FIG. 8 .
